US00D998631S

(12) **United States Design Patent** (10) Patent No.: **US D998,631 S**
(45) Date of Patent: ** *Sep. 12, 2023

(54) **DISPLAY SCREEN OR PORTION THEREOF
WITH A GRAPHICAL USER INTERFACE**

(71) Applicant: **MASIMO CORPORATION**, Irvine, CA (US)

(72) Inventors: **Keith Ward Indorf**, Lake Elsinore, CA (US); **Ammar Al-Ali**, San Juan Capistrano, CA (US)

(73) Assignee: **MASIMO CORPORATION**, Irvine, CA (US)

(*) Notice: This patent is subject to a terminal disclaimer.

(**) Term: **15 Years**

(21) Appl. No.: **29/824,367**

(22) Filed: **Jan. 24, 2022**

Related U.S. Application Data

(60) Continuation-in-part of application No. 29/778,924, filed on Apr. 15, 2021, which is a continuation-in-part of application No. 29/773,988, filed on Mar. 12, 2021, which is a division of application No. 29/666,325, filed on Oct. 11, 2018, now Pat. No. Des. 916,135.

CLAIM

The ornamental design for a display screen or portion thereof with a graphical user interface, as shown and described.

DESCRIPTION

FIG. 1 is a front view of a display screen or portion thereof with a graphical user interface in accordance with a first embodiment; and,

FIG. 2 is a front view of a display screen or portion thereof with a graphical user interface in accordance with a second embodiment.

The broken lines, including those showing a display screen or portion thereof and those depicting portions of a graphical user interface, form no part of the claimed design.

1 Claim, 2 Drawing Sheets
